UNITED STATES PATENT OFFICE.

WAINWRIGHT B. GERVAIS, OF CHICAGO, ILLINOIS, ASSIGNOR TO VARIETY FIRE DOOR COMPANY, OF CHICAGO, ILLINOIS, A CORPORATION OF ILLINOIS.

ELEVATOR DOOR AND THE LIKE.

Application filed June 17, 1922. Serial No. 569,049.

To all whom it may concern:

Be it known that I, WAINWRIGHT B. GERVAIS, a citizen of the United States, residing at Chicago, in the county of Cook and State 5 of Illinois, have invented a certain new and useful Improvement in Elevator Doors and the like, of which the following is a full, clear, concise, and exact description, reference being had to the accompanying drawings, forming a part of this specification.

My invention relates to elevator doors and the like.

Fire shutters are commonly employed for closing the door openings or passageways 15 leading to the elevator shafts of various buildings, particularly buildings employed for industrial purposes. In fact, modern fire regulations require the installation of such doors. These doors are commonly 20 divided horizontally at the center of the opening and one-half of the door is guided vertically upward, while the other half is guided vertically downward, the two being connected together and counterbalancing 25 each other. The space between door openings of adjacent floors of the building is usually less than the height of the sections 30 of the door and in order that proper opening of the doors be permitted, the practice has arisen of making one half or section—usually the lower section—fit closely adjacent the wall and spacing the other half—usually the upper section—away in an additional guide which is staggered for the 35 purpose of permitting overlapping of the adjacent sections of adjacent doors upon opening the same.

The matter of closing the space between the wall and the top part of the door sections spaced therefrom to prevent fire, 40 sparks, gases and the like from striking thru the openings into and from the elevator shaft has presented a difficult, practical problem. Various arrangements including 45 the suspension of fire stops from the lower door section of the door above for movement into position to close the space thru the lower door, by the closing of the upper door have been provided. These are complicated and expensive and their action is 50 dependent wholly upon the movement of the door sections. Furthermore, they must be moved from one position to another upon every operation of the door.

55 An object of my invention is the pro-

vision of a device normally positioned to permit proper overlapping of the adjacent sections and operated upon the occurrence of a fire or excessive temperature to close the space between the wall and the top part 60 of the door section spaced therefrom to prevent the passage of fire, sparks, gases and the like therethrough.

A further object is the provision of an improved, compact and affective device of 65 simple and inexpensive construction.

Further objects and advantages and the novel arrangement and structural features of my invention will appear from the following detailed description and the claims 70 taken with an inspection of the accompanying drawings in which;

Figure 1 is a fragmentary elevational view of the floor side of a door embodying my invention.

Fig. 2 is an enlarged vertical section taken substantially on the line 2—2 of Fig. 1;

Fig. 3 is a fragmentary enlarged horizontal section thru one of the guides or ways showing the upper section of one door 80 and the lower section of the door above in section.

Fig. 4 is a diagrammatic vertical section thru an elevator shaft showing the doors at the various door openings or passageways 85 equipped with an embodiment of my invention.

Referring to the drawings, 1 designates the elevator shaft of a building, 2 the door openings or passageways leading thru the 90 wall 3 from the various floors and 4 designates generally the doors provided at the several door openings or passageways 2.

Each of the doors or shutters is divided horizontally at the center of the opening 2 95 into an upper half or section 5 and a lower half or section 6, which sections are preferably connected together and counterbalance one another in the usual or any preferred manner. These upper and lower door sections are arranged in different vertical planes to permit overlapping with the adjacent sections of the doors above and below as shown in Fig. 1. In the particular embodiment shown the lower section 6 is fit snugly 100 adjacent the wall 3 and the upper half or section is staggered or spaced away to form a pocket 7 dimensioned to receive the lower section 6 of the door above upon upward movement of the section 5 in opening or 110

- downward movement of the section 6 of the door above in opening. This construction makes it possible to use such doors in buildings where the floor heights are relatively small as compared with the height of the door openings and where the space between the door openings of the respective floors is less than the height of the door sections.
- The elevator side of the wall 3 is usually faced along the opposite sides of the door opening 2 as shown at 8 and a vertical Z-bar 9 is secured along each of these facing members one at each side of the door opening by means of bolts 10 or otherwise as desired. The base flanges of these Z-bars provide for mounting the same in place while the outer flanges 11 with the connecting portions 12 define the guides or ways in which the door sections 5 and 6 are mounted for vertical movement.

Each of the door sections 5 and 6 comprises an angle iron frame 13 supporting a suitable sheathing 14 which is preferably corrugated and riveted, bolted or otherwise secured to the frame. Angle irons or bars 15 secured along the opposite sides of the frame 13 of each of the door sections provide flanges 16 which project laterally from the opposite sides of the respective door sections. The flange 16 projecting from the door 5 engages between the flange 17 of a U-shaped bar 18 and the flange 11 of the Z-bar 9. The U-shaped bar 18 is secured to the inner face of the connecting portion of the bar 9 between the flange 11 thereof and the wall 3. The flange 16 projecting from the door 6 engages between the flange 20 of the U-shaped bar 18 and the facing plate 8. The respective laterally projecting mounting and guides flanges 16 may be provided with suitable guide rollers 21 if so desired.

Arranged transversely across the top of the floor side of the upper door portion or section 5 and hingedly connected thereto by suitable hinges 25 is a plate or shutter 26. One of the leaves of each of the hinges 25 is secured to the plate or shutter 26 and the other leaf to the door section 5. Plates 27 secured to the door section 5 at the points of attachment of the hinges 25 facilitate the attachment of the hinges thereto. The plate or shutter 26 is normally held up flat against the top portion of the upper door section 5 by a suitable fusible link 27, one end of which is secured to the upper frame member of the door section while the other end is secured in a recess 28 formed in the upper edge of the plate or shutter 26 intermediate the opposite ends thereof. Upon the occurrence of a fire or a predetermined rise in temperature, the hinged shutter or plate 26 is released by melting of the fusible link 27 and when the door is closed drops into engagement with the wall 3 as indicated in dotted lines in Fig. 2, closing communica-

tion from the elevator shaft to the floor and vice versa and effectively preventing the passage of fire, sparks, gases and the like therebetween.

The normal position of the shutter 26 vertically against the door section 5 removes it from any possible interference with the proper positioning of the lower section of the door above in the pocket 7 upon upward movement of the section 5 or downward movement of the section 6 of the door above. There is no opening and closing of the shutter with every operation of the door, yet it is always ready to quickly operate to close off the space between the wall and the door section spaced therefrom. The opposite upper corners of the plate or shutter 26 are preferably offset toward the door as shown at 30 to secure the desired snug engagement of the upper edge of the shutter with the wall when it drops into co-operation therewith. Should the lower section of the door above be positioned in the pocket 7 when the link 27 melts, the shutter will drop into engagement with the door section positioned in the pocket.

Modifications and changes are contemplated within the scope of the invention which is pointed out in the appended claims.

I claim:

1. In combination, a wall having an opening therethrough, a door including a vertically movable portion spaced from said wall to form a pocket for the reception of a second vertically movable door portion, means carried by said first door portion for closing the space between said portion and the wall and means fusible at a predetermined temperature for retaining said closing means in open position.

2. In combination, a wall having an opening therethrough, a door section mounted adjacent the wall, a second door section spaced from the wall to form a pocket for the reception of said first door section, means carried by said second spaced away section for closing the space between the wall and said section and means for holding said last means open to permit overlapping of the section therewith.

3. In combination, a wall having an opening therethrough, a door section mounted adjacent the wall, a second door section spaced from the wall to form a pocket for the reception of said first door section, means for closing the space between the wall and said second section, and means fusible at a predetermined temperature for retaining said closing means in open position.

4. A counterbalanced fire door comprising upper and lower sections arranged in different planes and movable vertically in opposite directions in opening and closing, the upper section being spaced away from the door opening and means actuated inde-

pendently of the movement of said door sections for closing the space between said upper section and the wall, said closing means normally permitting overlapping of the sections therepast.

5. In combination, a wall having an opening therethrough, a door section mounted adjacent the wall, a second door section spaced from the wall to form a pocket for the reception of said first door section, a shutter hingedly attached to said second spaced away section and normally lying flat against the same so as not to interfere with the positioning of said first section 10 in the pocket formed therefor by the spacing of said second section from the wall, said shutter being adapted to close the space between said second spaced away section and the wall to prevent communication therethrough.

6. In a door of the class described, a pair of door sections arranged in different planes and movable vertically in opposite directions in opening and closing, the upper section being spaced away from the wall to provide a pocket for the reception of the lower section of the door above, a shutter hingedly attached to said upper spaced away section and adapted for closing the 25

space between said section and the wall to 30 prevent communication therethrough, and means fusible at a predetermined temperature for normally holding said shutter substantially flat against the upper door section so that the positioning of the lower section of the door in the pocket formed therefor will not be interfered with.

7. A counterbalanced fire door comprising upper and lower sections arranged in different planes and movable vertically in 40 opposite directions in opening and closing, the upper door section being spaced away from the door opening, a shutter arranged along the upper edge of said upper door section and hingedly attached thereto, said 45 shutter having its opposite upper edges offset toward the door and being adapted to swing into cooperation with the wall to close the space between said upper section and the wall, and a fusible link secured at 50 one end to the upper door section and at its opposite end to the shutter hingedly attached thereto for holding said shutter in open position.

In witness whereof, I hereunto subscribe 55 my name this 13th day of June, 1922.

WAINWRIGHT B. GERVAIS.
